UNITED STATES PATENT OFFICE.

PHILIP H. UNSINGER, OF FREMONT, OHIO, ASSIGNOR TO THE UNSINGER MANUFACTURING COMPANY, OF FREMONT, OHIO, A CORPORATION OF OHIO.

CUTTING DEVICE.

Application filed April 28, 1924. Serial No. 709,417.

To all whom it may concern:

Be it known that I, PHILIP H. UNSINGER, a citizen of the United States of America, residing at Fremont, Sandusky County, 5 Ohio, have invented new and useful Cutting Devices, of which the following is a specification.

This invention relates to cutters, slitters and the like.

10 This invention has utility when incorporated in tools of a draw knife type for cutting packing board, opening cartons and packing boxes and cutting material of the general character of fibre containers.

15 Referring to the drawings:

Fig. 1 is a side elevation of the device showing its manner of operation;

Fig. 2 is a side view of the blade mounting end of the device, parts being broken 20 away;

Fig. 3 is a plan view of the device, parts being broken away; and

Fig. 4 is a view on the line IV—IV, Fig. 2.

25 The main body or handle portion 1 is shown as comprising a casting which may advantageously be of aluminum. Centrally of this main body member 1 is enlarged portion 2 which serves as a means for facilitating gripping for effective drawing action of the tool. One end of the main body or handle 1 is tapered to form a wedge 3. This wedge portion 3 serves as a means for effecting opening of boxes and cartons, or 30 for starting an opening in a box or carton where it is desired to unseal or pry loose a side or flap.

35 Remote from the wedge portion 3 the handle 1, 2, is provided with slot 4 in which tool 5 is pivotally mounted on screw 6. This tool 5 may be swung on its pivot to a position for cutting at which position the tool extends outwardly from the main body 1 or the tool may be swung inwardly into the slot at which position the handle 1 acts as a sheath for the tool. The outward swing of the tool 5 is limited by pin 7 anchored in the handle 1 transversely of the slot 4 at a point for stopping the tool 5 at a fully 40 open position for an effective drawing.

45 The tool 5 is shown as of thin stiff cutlery steel with a plurality of cutting edges or blades. First cutting edge 8 serves partially to sever the stock and in so doing tends to crowd the stock down; while the

second cutting edge 9 which is at an angle to the first cutting edge, effects the cutting travel inward from the opposite side of the stock and holds the blade 8 into the stock. The blades or edges 8, 9, are each sharpened 60 from both sides to be central of the tool 5 for ease in draft control. The edges 8, 9, are spaced by throat 10. It is thus clear the normal tendency of the blade 8 is to work out of the stock and away from its 65 cutting region. The blade 9 has normally a tendency to work through and out of the stock. With the draft angle having its major component proportionally large in the cutting direction, the draft on the tool holds 70 the blades into the stock in their aligned travel.

75 The blades herein disclosed are especially adapted for cutting corrugated board, card board and even quite heavy fibre board.

75 The two cutting edges 8, 9, are on the same side of the tool while the tool, on its opposite side has serrations 11 which extend outside the slot 4 when the blade is sheathed within the slot. These serrations serve as 80 a means for readily effecting opening or unsheathing of the tool. By bringing the serrations in contact with some stock in a sweeping motion, the tool is rocked on its pivot 6 to a partially open position, from 85 which a complete opening may be effected by taking hold of the exposed portion of the tool to shift the tool to ride against the stop or pin 7.

85 The screw 6 in addition to providing a 90 pivot mounting for the blade carrying tool also is used slightly to bind the blade between the sides of the slot 4. This tends to give stiffness to the blade for firm holding against vibration in use, and frictionally 95 resists shifting of the tool as to the handle.

95 The tool of this disclosure is especially adapted for use where cartons of fibre or corrugated board are to be opened. The two intersecting direction cutting edges give 100 a maximum of cutting efficiency as the cutting edge 8 partially cuts the stock while the second edge 9, in addition to finishing the cut, tends to draw and hold the edges into the stock, due to the direction of draft. 105 As the tool is thin, it does not crowd the stock and thereby build up resistance to cutting travel. The blades 8, 9, align in their cutting travel and as their edges are sharpened from both sides and in a common 110

plane, there is a minimum of resistance. The tapered extension 3 of the handle from the grip portion 2, conveniently rides against the wrist of the operator to supplement the grip in providing easy directing means for tool draft in the cutting operation of the device.

What is claimed and it is desired to secure by Letters Patent is:—

- 10 1. A cutting device comprising a tool, said tool embodying a plurality of simultaneously cutting edges, said cutting edges lying in a common plane, being of different lengths, and extending at different angles from the line of normal draft of the tool, and spaced from each other by a throat directly opposing one of said cutting edges.
- 15 2. A cutting device embodying a tool mounting member, a tool carried thereby and having a plurality of simultaneous cutting edges lying in a common plane, being of different lengths, and extending at different angles from the line of normal direction of draft of the tool and separated by a throat, and means in the plane of the cutting edges for limiting the movement of the tool in its mounting member.
- 20 3. A cutting device comprising a handle member embodying a slot, and a tool pivotally mounted in said slot for sheathing therein, there being in the plane of the tool means engageable for unsheathing the tool, said means embodying serrations on said tool extending outside said slot to project from the handle when the tool is sheathed within said slot, whereby pulling of the handle with said serrations held against a surface to be resisted thereby results in a swinging of the tool on its pivot out of 35 sheathing position in the handle.
- 30 4. A cutting device comprising a tool having a plurality of transverse simultaneous cutting edges terminating at a common side to have exposed spaced ends, said cutting edges being of different lengths and extending at different angles from the normal di-

rection of draft of the tool, one of said cutting edges disposed in draft of the device to serve as a partial cutter of sheet material into one side thereof and another of said cutting edges in said draft disposed to serve as an aligned opposing cutter in a common plane of said material into the opposite side of the material and toward the cutting action of the one.

55 5. A draw knife hook having a handle, a down draft directing cutting edge adjacent the handle having clearway forwardly of the plane of said edge in the perpendicular bounds of said plane, and following said down draft cutting edge, an up draft simultaneously effective-directing cutting edge, said edges being in a common plane of different lengths spaced by a throat, and extending at different angles from the line of the normal direction of draft as effected by the handle.

60 6. A tool comprising a pair of simultaneous cutting blades of different lengths in a common plane for aligned common direction cutting travel and having their normal draft action at different angles, such action of one blade tending to crowd material acted upon toward the other blade, and a handle having a general direction line 65 away from which one of said blade edges extends to terminate at a throat.

65 7. A draw knife having a handle, and extending therefrom a tool providing a pair of simultaneous cutting knife edges in a common plane for simultaneous cutting draft, said edges being of different lengths, spaced by a throat, and of different angles from the line of the normal draft as effected by the handle, one of said edges as in advance of the other being clear for thrusting into and out of sheet material perpendicularly as to the line of extent of said edge within the plane of its draft.

In witness whereof I affix my signature.

PHILIP H. UNSINGER.
